UNITED STATES PATENT OFFICE

2,588,000

SUCTION CLEANER WITH BRUSH FOR
CLEANING WALLS

Albert Roy Hines, Columbus, Ga.

Application January 29, 1946, Serial No. 644,017

2 Claims. (Cl. 15—320)

1

This invention relates to improvements in cleaning apparatus and more particularly to means for cleaning Venetian blinds, walls and other surfaces.

One of the objects thereof is to provide a simple, efficient and inexpensive hand sprayer gun designed to be used for the purpose of brushing with a fluid spraying action the surface to be cleaned in such a manner that, by moving the cleaning means therein about and over various points of the surface to be cleaned all parts thereof can be given a thorough cleansing.

A further object thereof is to provide a hand sprayer gun with a rotary brush with which is effectively associated fluid spraying and fluid suction means for the purpose of causing the brush to spread a cleansing fluid over the surface it scours as well as for the purpose of exhausting out of the sprayer gun the particles of fluid with its content of dirt and impurities so as to remove the moisture deposited upon the surface being cleaned.

Another object thereof is to provide a hand operated and controlled sprayer gun with the parts so shaped, arranged and constructed that cleansing fluid will be sprayed continuously over the periphery of a rotating brush, and moisture from the surface already cleaned by the spraying fluid continuously sucked out through the rotary brush to a point of convenient discharge from the gun.

A still further object thereof is to provide a hand sprayer and suction gun with novel brushing means in the form of a detachable interchangeable brush head adapting the gun for use in the cleansing of various different surfaces in some way part of or connected with a building.

In carrying out the foregoing objects I have designed a hand held and hand operated and controlled outfit that carries a suitable pumping medium for both injecting a cleansing fluid thereinto as well as drawing out said fluid by a suction action after the same shall have come in contact with the surface being cleansed. To this end there is disclosed a system of fluid injecting ducts in both the sprayer gun and brush in the same parts of the gun and brush attachment, establishing a desirable cycle or circulation of fluid to and from the surface being cleansed with the view of continuously supplying fresh cleansing fluid to the discharge end of the gun as fast as the dirt loosening and dirt soaked exhaust fluid is drawn out by suction therefrom.

A further object of this invention is to pro-

2

vide means for coupling together detachably the sprayer gun and the brush holder in such a manner that a fluid tight seal is maintained effectively between the abutting ends thereof and a continued line of intercommunication maintained at all times both in the sprayer gun and in the brush holder for the passage of cleansing fluid and exhaust fluid therein and thereout.

With the above and other objects in view my invention consists in the combination, arrangement and details of construction disclosed in the drawings and specifications, and then more particularly pointed out in the appended claims.

In the drawings, wherein similar reference characters designate similar parts throughout the drawings,

Figure 1 is a longitudinal sectional view of one form of my invention.

Figure 2 is a fragmental detail side elevation of the confronting ends of the sprayer gun and brush holder in the act of being coupled together,

Figure 3 is a front end elevation of Figure 1 with the brush removed,

Figure 4 is a front elevation of the drum end of the brush holder in which is housed the rotary brush,

Figure 5 is a cross section taken on line 5—5 of Figure 1, and

Figure 6 is a section taken on line 6—6 of Figure 1.

Referring to the drawings, which are merely illustrative of my invention, I disclose the various parts thereof. There is disclosed a sprayer gun comprising as its major length a cylindrical body 10 formed at its intermediate part with an extension bulge 11, and at its outer or forward end preferably with a reduced cylindrical terminal 12. Operatively held in fitted relation abuttingly against the front face of the stem 12 is a gasket 13 of suitable sturdy material. In line with the cylindrical body 10 at its rear end is a slotted handle 14, the slot of which is designated 15.

Movably seated snugly in said handle 14 is a lever or trigger 21, preferably wedge-shaped, having its narrow upper end mounted to swing upon a pivot pin 26 extending in said handle 14. The trigger 21 is operatively connected to an electric switch, not shown, whereby depression of the trigger 21 will close the switch thereby completing the circuit to the motor 31.

The extension bulge 11 along the lower side of the intermediate portion of the body 10 is formed with several annular internally threaded pro-

jections 17, 18 and 19, which are adapted to secure the upper end of containers 57, 58 and 59 to the body 10. The containers 57 and 58 contain a cleaning solution and water respectively.

A passage 26 in the body 10 extends through the bulge 11 and communicates with a tube 51 which projects downwardly into the container 57.

A passage 27, also in the bulge 11, communicates between the passage 26 and the opening formed by the annular projection 18. A tube 52 extends from the passage 27 downwardly into the container 58.

The containers 57, 58 and 59 form a lower handle for the body 10, such handle being generally designated as 16.

The passage way 26 communicates with a circular supply duct 29 disposed concentrically of body 10, from which extend circumferentially spaced apart elongated ducts having their axes parallel to the axis of the body 10 and open as at 30 out of the annular conical head 31 formed centrally of the washer or closure jacket 13, to provide sprayer outlets 32. The washer 13 is formed with an annular outwardly flaring counter seat or channel 33 around the annular bead 31, and circumferentially extending series of ducts 40a have outlets therein which extend inwardly of said body 10 parallel to the axis thereof.

There is an internal chamber in Figure 1 which houses a motor 31, having a shaft 36 which extends through the chamber H in cylinder body 10 so as to project with its outer end into washer 13 and dispose its coupling end 38 in the hollow of the annular bead 31 thereof. The shaft 36 is rotatedly held in ball bearing sections 42 and 41, in which the balls 43 encircle the shaft.

A pump or fan 45 is fixed to the other end of the shaft 36 and is housed between two chambers S. Rotation of the pump 48 forces air and fluid downwardly through the passage 50, and a tube 53 which extends into the container 59, thus forming a suction in one of the chambers S, and the passages longitudinal which are directly communicated with the chambers S, as 45 and 47.

The container 59 has a volume of nearly the combined volume of the containers 57 and 58, so that the water and cleaning solution after use are returned to the container 59. A vent passage 48 in the body 10 communicates with the container 59 and the outside air by way of tubes 54 and 55 which extend into the container 59, as tube 54, and above the body 10, as tube 55.

I provide a brush carrier or holder as a separate part of the sprayer gun apparatus designed for detachment from the latter. It is composed of a cylindrical body or stem 61, which, at its inner end, is formed with an annular peripheral conical bead 63 which encircles an annular channel or seat 64, which encircles a conical lip 65. Formed at the outer end of the brush holder is a drum of larger diameter than body 61, formed by means of annular flange 66 which has a rounded periphery, and having a hollow housing defining the interior of the drum.

Formed at the outer part of body 61, which also forms the back wall of the drum 66 is an outwardly projecting annular conical bead 74 enclosing an interior cylindrical seat 75. This bead extends into the rear end of the housing 61, and a circumferentially extending series of ducts 73 open out therefrom into said housing, which ducts extend axially along the length of the stem 61 and also open out of the annular channel 64 thereof. A circumferentially extending series of

ducts are also formed in the periphery of the drum flange 66 such that they follow the round exterior contour thereof and open out of the periphery thereof at one point, and extend down as at 79 radially of body 61 so as to terminate in a plane, with the periphery of the bead 74. These ducts are connected by a circular duct 72a formed in body 61 with which communicate a radially disposed series of ducts 72 extending axially of body or stem 61 and opening out of the peripheral conical bead or lip 63. A circular duct 72b also communicates with all of the ducts 73 which open out of the bead 74.

The brush carrier or holder is formed centrally with a bore or chamber 76, at the opposite ends of which are lodged ball bearing sections 77 and 78 which confine anti-friction balls 79 around a shaft 80 passing through chamber 76 so as to extend into housing 67 of the drum 66, where it terminates in an anchor head 81 operatively seated centrally in a cylindrical brush back or head 82 of a size and diameter to snugly revolve in the drum. Bristles 83 extend over the effective area of the brush back in close proximity, which bristles also project beyond and outside of the drum 66. The rear face of the brush back 82 is in close proximity to the annular bead 74 and formed in this brush back concentrically of and opposite directly to and in confronting relation to this bead 74 are concentric rows of through ports 84 which communicate with the interior of the housing at their inner ends and open out of the brush back at their outer ends.

As a means of detachably connecting or coupling the brush carrier or holder to the sprayer gun proper I disclose the following. At diametrically opposite points of cylindrical body 61 of the brush holder (Figure 2) I form suitably shaped cleats 85 having notches 86 therein. Looped links 87 are designed to be carried over so as to be introduced into said notches 86 of the cleats 85. The inner ends of these links 87 at diametrically opposite points of the body 10 of the gun, are pivotally connected at 88 intermediate the length levers 89. The levers 89 are mounted at their inner ends upon pivot pins 90 passing through lugs 91 formed upon the gun body 10. The levers 92 have handle extensions 92 preferably made of resilient material and arched in contour.

I will now describe the operation of the apparatus. The operator takes hold of the form of brush holder shown in Figure 1 if he wants to clean walls and similar surfaces of a house or room. Assuming that first he wants to couple the type of brushing device shown in Figure 1, he draws together the confronting ends of the brush holder 61 and outer reduced end 12 of the sprayer gun as illustrated in Figure 2. He hooks on loop links 87 of the gun in the notches 86 of the cleats 85 of the brush holder, and as he takes hold of the lever handles 92 of levers 89 and throws them over completely so that they overlie the exterior surface of the gun cylinder 10, it will be seen that the rear end of the brush holder is contacted abuttingly with the front end of the gun.

This action couples the two parts of the cleaning apparatus for joint operation. The operator next takes hold of the gun handle 16 in one hand and may use the other hand to take hold of the finger hold 14 so that with one hand he can steady the machine and position the brush end thereof against the wall or other flat surface to

be cleaned and with the other hand he can operate the trigger 21 to control the fluid in the gun and brush carrier. When he presses the trigger, the switch, not shown, completes the electrical circuit to the motor 37 and the pump 46 is set into operation, creating a suction in one of the chambers S. This suction is created also in the passages 45, 47 and 40a in the body 10, and the passages 72 and 70 in the brush holder body 61. As the brush is being held against a wall, the suction will also be created in the passages 84 and 73 of the brush holder body 61 and passages 32, 26 and 27 in the body 10. Thus the water in container 58 will be sucked up through the passage 27 and mixed with the cleaning solution, being sucked from container 57, in the passage 26, thence to the circular duct 29 and through the annular outlets 32.

Under suction the cleansing fluid flows through ducts 73 in the brush holder body 61, around circular duct 72b, and thence out of the outlet ports which open out of the annular bead 74 formed upon the back wall of the drum 66. Suction from the pumping apparatus sucks cleansing fluid directly out of the concentric rows of discharge ports 84 formed centrally of the brush back 82. In the meantime the electrical motor 37 has been in operation to rotate the coupled sections 36 and 80 of the line of shafting from this motor, due to the coupling end 38 of one shaft fitting into the coupling end 38a of the other shaft. This rotates the brush and carries the lines or rows of bristles on the brush back in a rotary cycle of movement. This action of the brush receiving the discharged jets of cleansing fluid from its center as it rotates causes the bristles 83 of the brush, which has been pressed by the operator against the surface to be cleaned, to convey or throw by centrifugal action, the dirt loosened and dirt soaked exhaust fluid churned by the brush over the surface it is desired to wash and clean by a scouring action, towards the periphery of the cylindrical brush back, where the continuously revolving brush swirls the exhaust dirt soaked fluid in the annular groove 69 in the periphery of the drum, from which the exhaust fluid is sucked out through the ducts 70 communicating with circular groove 69 (Figure 4), and by way of ducts 72, and the ducts 40a in the sprayer gun, which open out into the annular channel into which the annular bead 63 of the brush holder body 61 has been fitted, upon intercoupling of the holder and gun. The exhaust fluid, thus passes through the gun and is discharged into circular duct 44 and thence by way of branch ducts 45 to the suction chamber S, and forced into the waste container 59.

I do not mean to confine myself to the exact details of construction disclosed in the drawings and specification, but mean to cover all variations set forth in the appended claims.

What I claim is:

1. A surface cleaning device comprising a cylindrical body, an electric motor in said body, a suction fan housing having a pressure side and a suction side in said body, a suction fan in said suction fan housing operatively connected to said motor, said body formed with circumferentially spaced apart fluid inlet passages axially parallel to the axis of said body, opening through one end of said body and communicating with the suction side of said housing for the admission of fluid therein, said body formed with circumferentially spaced apart fluid discharge passages

opening through said one end of the body and through one side thereof, means supporting a cleaning fluid container on a side of said body in communication with said fluid discharge passages, means supporting a fluid container on a side of said body in communication with an opening from the pressure side of said fan housing, a shaft on said motor coaxial with said body in said one end thereof, a brush supporting housing formed with fluid inlet and discharge passages longitudinally thereof, a shaft rotatable in said brush housing, a rotatable brush at one end of said brush housing operatively connected with said second named shaft interengaging coupling means carried by the confronting ends of said shafts, an annular suction nozzle carried by said brush housing enveloping said brush, said fluid passages opening interiorly of said nozzle, said latter fluid passages opening through the ends of said brush housing, and clamping means securing said brush housing on said cylindrical body, said fluid inlet and discharge passages of said brush housing and body being in alignment in the clamped position of said brush housing on said cylindrical body.

2. A surface cleaning device comprising a body, a suction fan in said body, a motor operatively connected to said fan, a cleaning fluid container supported on said body, an exhaust fluid container supported on said body, said body formed with suction passages between one end thereof and said cleaning fluid container for removing fluid therefrom, and with passages between said exhaust fluid container, said fan and said one end whereby fluid drawn from said first container may be returned to said latter container, a drive shaft operatively connected to said motor in said one end of said body, a brush housing, a brush rotatable in said housing, a shaft operatively connected to said brush, said housing formed with fluid inlet passages opening adjacent said brush and opening from one end thereof, an annular suction nozzle carried by said brush housing enveloping said brush, said fluid passages opening interiorly of said nozzle, and fluid discharge passages opening through both ends of said housing, means removably coupling said brush housing to said body with the inlet and discharge passages in registry with the passages of said body to said cleaning fluid and exhaust containers respectively, and inter-engaging coupling means removably connecting said shafts together.
